UNITED STATES PATENT OFFICE.

ALBERT LONG, OF LAWRENCE, AND ROBERT FOSTER, OF METHUEN, MASSACHUSETTS; SAID FOSTER ASSIGNOR TO SAID LONG.

DRAWING-OFF MECHANISM FOR CIRCLE-COMBS.

No. 862,980.

Specification of Letters Patent.

Patented Aug. 13, 1907.

Application filed December 18, 1903. Serial No. 185,623.

To all whom it may concern:

Be it known that we, ALBERT LONG and ROBERT FOSTER, of Lawrence and Methuen, respectively, in the county of Essex and State of Massachusetts, have invented certain new and useful Improvements in Drawing-Off Mechanism for Circle-Combs, of which the following is a specification.

This invention is an improvement on the drawing-off mechanism for circle combs described in our Letters 10 Patent Nos. 606,564, June 28, 1898, and 679,975, August 6, 1901, which includes drawing-off devices composed of smooth-surfaced co-acting cylindrical rolls instead of fluted rolls and leather aprons.

The object of the present invention is to more effectively 15 guide the fringe toward the drawing-off device of the large circle by means of an improved licker-in construction and to guide the fringe to said licker-in; to furnish an improved and economical means for propelling the sliver between the drawing-off devices of 20 the large and small circles; to effectively clear the rolls; to improve the means for mounting and guiding the licker-in and the sliver-propelling means intermediate between the drawing-off devices; to intercept air currents acting on the fringe; and to facilitate the passage 25 between the rolls of foreign substances in the wool.

Of the accompanying drawings,—Figure 1 represents a horizontal section of drawing-off mechanism for circle combs constructed according to our invention. Fig. 2 represents an elevation, looking toward the licker-in 30 and the drawing-head of the large circle. Fig. 3 represents a section on line 3—3 of Fig. 2. Fig. 4 represents a vertical section of the support for the outer pulley of the licker-in belt. Fig. 5 represents a section on line 35 5—5 of Fig. 2. Fig. 6 represents a detail end elevation of the fringe-guide and concaver for the licker-in belt. Fig. 7 represents a section on line 7—7 of Fig. 2. Fig. 8 represents a detail elevation of the clearing device for one of the rolls of the small-circle drawing-off device. Fig. 9 represents a diagrammatic plan view of the arrangement of parts with respect to the large and small 40 circles. Fig. 10 represents a section on line 10—10 of Fig. 2.

The same reference characters indicate the same parts in all the figures.

45 In the drawings, 20 (Fig. 9) is a portion of the large toothed circle of a Noble comb and 21 is the small toothed circle.

22 denotes as a whole the drawing-off head of the large circle composed of the three smooth-surfaced 50 cylindrical drawing-off rolls 23 24 25 geared together and driven by a shaft 26 on the central roll, and 27 denotes as a whole the drawing-off head of the small circle composed of smooth-surfaced cylindrical rolls 28 29 30 similarly geared together and driven by a shaft 31 on 55 the middle roll. It will be noted in Fig. 2 that

the roll 23 of the large-circle head is formed with a circumferential groove 32 for properly guiding and concentrating the fringe into a sliver, as described in our aforesaid patent No. 679,975, the depth of said groove being exaggerated for clearness.

33 is the licker-in belt adjacent the large circle for slanting the fringe thereof into the nip of the rolls 23 24, said belt being supported at its outer end on a driving pulley 34, and at its inner end on idle pulley 35. The shaft 36 of the pulley 34 is journaled in a bearing 37 65 formed on a plate 38 (Figs. 2 and 5) which is adjustably secured to a portion 39 of the comb-framework by a bolt 40 occupying slot 41 in the plate, whereby the pulley 34 is given an adjustment laterally to increase or decrease its distance from the toothed circle 20 70 and also longitudinally of the belt 33 to take up the slack in said belt. On the lower end of the pulley-shaft 36 is a bevel gear 42 meshing with a complementary bevel gear 43 secured by set-screw 44 to a horizontal shaft 45, the latter connecting through 75 bevel gears 46 47 with the driving-shaft 26 of the large-circle drawing-off head whereby the belt-pulley 34 is driven from said head. A bracket 48 embracing the shafts 26 and 45 as shown in Fig. 3, permits the lateral adjustment of the bearing 37 here- 80 inbefore mentioned, and the adjustment for stretch of the licker-in belt is attained by shifting the gear 43 and a bracket 49 which embraces the shaft 45 and bearing 37, said bracket being secured by set-screw 50 to said bearing, whereby the pulley 34 may be adjusted 85 vertically.

The belt 33 travels faster than the peripheral speed of the rolls 23 24 25 as will be evident from an inspection of the drawings.

The inoperative stretch of the licker-in belt 33 is 90 guided by an abutment 51 on which is a bracket 52 supporting a concaved or V-shaped belt-former 53. The latter rests behind the operative stretch of the belt 33 and imparts a concave form to the belt as seen in Fig. 7, whereby the fringe is more effectively guided 95 and concentrated within the zone of the belt and properly directed toward the groove 32 of the drawing-roll 23. Also mounted in the bracket 52 is a wire fringe-guide or support 54 interposed between the licker-in belt and the toothed circle for sustaining the fringe 100 projecting from said circle and properly maintaining it within the zone of the belt. Said fringe-guide extends in a general horizontal direction and is curved downwardly at both ends to give the fringe a gradual entrance and delivery. The guide 54 has a vertical 105 stem or shank 55 secured by a set-screw 56 in the bracket 52 for purposes of vertical adjustment.

The lower side of the pulley 34 is provided with a horizontal flange 57 extending a substantial distance toward the large circle underneath the fringe, the ob- 110

ject of which is to intercept the resultant down draft of air which is encountered in most combs and is due to the heating of the air below the circle by the steam-box, which down-draft has formerly tended to slant 5 the fringe downwardly.

It will be noted in Fig. 1 that the first roll 23 and last roll 25 of the large-circle drawing-head are in contact with each other, these rolls rotating in the same direction and their contacting portions accordingly 10 traveling in opposite directions. The roll 25 therefore acts as a clearer for the roll 23, serving to prevent the passage of fiber around the roll 23 instead of onward with the sliver. Said roll 25 also is mounted in a holder yieldingly actuated by adjustable spring pressure to 15 ward the central roll 24 and movable therefrom against such pressure, as in our prior patent No. 679,975, and in addition the holder is given such looseness in its guides that its end which holds the roll may move laterally. The spring pressure normally holds roll 20 25 in contact with roll 23, but when a lump of matted wool, a bur, twig or bit of other foreign matter is carried into contact with the rolls with the sliver, roll 25 is enabled to give way instantly in a lateral direction and subsequently to be forced radially away from 25 the central roll against the spring pressure without cramping or binding the holder against its guides.

58 is a carrying belt mounted on a driving pulley 59 at the small-circle drawing-head and an idle pulley 60 at the large-circle drawing-head for the purpose of 30 propelling the sliver from the large circle between the heads and introducing it to the nip of the small-circle rolls 28 29, where it combines with the sliver from the small circle. Contrary to our former practice, this belt is the sole intermediate propelling means and is 35 opposed on the other side of the path of the sliver by a stationary elongated guide 61, preferably made of polished metal against whose surface the sliver slips with small friction. This guide is adjustable toward and from the operative stretch of the belt by means 40 of a bracket 62 having bolt and slot mounting. An adjustable idle pulley 63 preserves the tension of the belt. The operative stretch of belt 58 being on the side of the path of the sliver opposite to the throat between the large and small circles, said stretch may 45 be of such length as to propel and support the sliver throughout the desired distance between the heads. It will be seen that the pulley 59 is driven by gear 64 on the shaft 31 of the small-circle drawing-off head and an intermeshing gear 65 on the pulley-shaft. The 50 belt 58 is then driven from the small-circle drawing-off head and the belt 33 independently from the large-circle drawing-off head. By reason of this construction and by adjusting the belt 58 to proper length, the drawing-off head may be fitted to many different 55 styles of combs.

In connection with the middle roll 29 of the small-circle head we provide an improved clearer for preventing the fiber from following the periphery of said roll, the same comprising a pair of flexible plates 66 60 slightly flaring at the operative ends and embracing between them an arc of the roll. These plates are riveted to a stouter plate 67 mounted on an adjustable bracket 68. These clearers 66 automatically position themselves in a lateral or horizontal direction with 65 respect to the surface of the roll 29 and by reason of a

slight elasticity of the plate 67 permitting a limited pivotal or swinging movement thereof with respect to its fixed point or support, the plates 66 have a joint swinging movement, whereby lateral pressure on one is communicated to the other through the plate 67, 70 the plates being thereby automatically positioned.

We provide the nipping zone of the grooved roll 23 of the large-circle drawing-head with an arched or substantially V-shaped longitudinal groove 70 occupying the bottom of the circumferential groove and composed of upper and lower limbs converging backwardly or in a direction opposite to the direction of rotation of the roll. More than one of these grooves may be provided if desired. The object of the groove is to allow for the passage of foreign matter, such as particles of burs which are found in the wool which have heretofore accumulated to some extent at the entrance to the nip. By inclining the limbs of this groove to the longitudinal elements of the roll and converging said limbs backwardly, two purposes are effected. First, 80 any backward drag or slip of the sliver relatively to the roll will drag any foreign particle which enters the groove toward the middle or deepest part of the circumferential groove 32 where the sliver is thickest, thereby affording a cushion for the foreign particle and facilitating its onward passage; second, such inclination carries the edges of the groove 70 progressively and not abruptly past the nipping point, therefore avoiding any tendency to cut the fiber.

It will be understood that the improvements herein 95 set forth are not confined to the exact construction shown, but may be variously embodied without departing from the spirit of the invention.

We claim:—

1. In a drawing-off mechanism for circle combs, the 100 combination with the large toothed circle, of a drawing-off device therefor mounted within the circle, a licker-in belt antecedent to said drawing-off device and speeded faster than the latter for slanting the fringe toward said device, and a stationary guide between said circle and belt for 105 elevating and sustaining the fringe within the zone of said belt.

2. In drawing-off mechanism for circle combs, the combination with the toothed circle, of a drawing-off device, and an endless licker-in belt therefor having an operative 110 stretch concaved to form a longitudinal channel or trough for the sliver.

3. In drawing-off mechanism for circle combs, the combination with the toothed circle, of a licker-in belt to slant the fringe thereon, and a concave former back of the operative stretch of said belt for imparting a trough-shape to 115 said stretch.

4. In drawing-off mechanism for circle combs, the combination with the toothed circle, of a drawing-off device therefor including a smooth-surfaced cylindrical roll 120 formed with a circumferential sliver-groove, and a concave licker-in to direct the fringe into said groove.

5. In drawing-off mechanism for circle combs, the combination with the toothed circle, of a drawing-off device therefor including a smooth-surfaced cylindrical roll 125 formed with a circumferential sliver-groove, and a licker-in belt having an operative stretch substantially aligned with said groove and concaved to form a longitudinal fringe-guiding channel.

6. In drawing-off mechanism for circle combs, the combination with the toothed circle, of a concaved drawing-roll, a concaved licker-in antecedent thereto, and fringe-supporting means adjacent the circle for directing the fringe into the concavity of said licker-in.

7. In drawing-off mechanism for circle combs, the combination with the toothed circle, of a licker-in belt adjacent the circle concaved to form a longitudinal channel 135

for the sliver, and fringe-sustaining means between said belt and the circle arranged to direct the fringe into said channel.

8. In drawing-off mechanism for circle combs, the combination of a smooth-surfaced drawing-off roll, and a pair of flexible clearers embracing between them an arc of the roll and connected and mounted for joint lateral movement.

9. In drawing-off mechanism for circle combs, the combination with the drawing-off devices for the large and small circles, of a licker-in for the large circle, sliver-propelling means interposed between the drawing-off devices connections between the large-circle drawing-off device and the licker-in for driving the latter, and independent connections between the small-circle drawing-off device and the sliver-propelling means for driving said means.

10. In drawing-off mechanism for circle combs, the combination with the toothed circle, of a licker-in belt therefor, a drawing-off device for said circle having an upright driving-shaft, a driving-pulley for said belt adjustable laterally of the toothed circle and longitudinally of the belt, driving connections between said shaft and pulley including gearing at the shaft, gearing at the pulley, and a substantially horizontal angularly-adjustable shaft connecting said gearing, and provisions for adjusting the pulley gearing longitudinally of said horizontal shaft.

11. In drawing-off mechanism for circle combs, the combination with the toothed circle, of a drawing-off device, a licker-in belt to slant the fringe toward said device, and a pulley supporting said belt and having a flange extended a substantial distance toward the circle to intercept air-currents traversing the fringe.

12. In drawing-off mechanism for circle combs, a smooth-surfaced drawing-off roll formed on its nipping-zone with a longitudinal groove or gutter.

13. In drawing-off mechanism for circle combs, a smooth-surfaced drawing-off roll formed on its nipping-zone with a groove inclined to the longitudinal elements of the roll-surface.

14. In drawing-off mechanism for circle combs, a smooth-surfaced drawing-off roll formed on its nipping-zone with a circumferential groove, and a longitudinal groove in the bottom of said circumferential groove having limbs converging in a direction opposite to the direction of rotation of the roll.

In testimony whereof we have affixed our signatures, in presence of two witnesses.

ALBERT LONG.
ROBERT FOSTER.
